UNITED STATES PATENT OFFICE.

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHEET-FEEDING MACHINE.

Application filed June 18, 1919. Serial No. 305,037.

To all whom it may concern:

Be it known that I, WILLIAM C. BAXTER, a citizen of the United States, residing at Beverly, in the county of Essex and State 5 of Massachusetts, have invented certain Improvements in Sheet-Feeding Machines, of which the following description in connection with the accompanying drawings, is a specification, like reference characters on the 10 drawings indicating like parts in the several figures.

This invention relates to sheet feeding machines and more especially to sheet feeding machines which feed sheets from a stack, 15 the stack supporting means and the sheet feeding means being movable relatively to each other as the sheets are fed to keep the stock in operative relation with the sheet feeding means.

It is an object of the invention to provide 20 a reliable and effective mechanism for automatically feeding sheets from a stack, the construction and arrangement being preferably such that the feeding means in co-operation 25 with a member controlled by the stack determines the position of the stack during sheet feeding operations. Preferably the feeding means is arranged to be stationary in its vertical plane so as to limit positively 30 the extent of upward movement of the stack whereby the sheets are fed forwardly successively in the same plane.

An important feature of the invention resides 35 in a simple, strong and inexpensive construction, comprising a cable and drum mechanism, for lifting the stack of sheets to the feeding means and maintaining the stack in proper position during successive sheet feeding operations.

A further feature of importance relates to 40 the arrangement of a carriage for carrying a plurality of stacks of sheets so that the operator may load sheets at one station while the machine continues in operation at another station, thus making it possible for 45 an operator to attend a number of machines provided with the automatic sheet feeding means of this invention, the stack lifting means being so constructed as to receive the 50 stack support of the carriage as the latter is shifted to bring a fresh stack of sheets into alignment with the sheet feeding means.

Other features and objects of the invention will be apparent from the following detailed description and will be pointed out 55 in the claims.

In the drawings—

Fig. 1 is a side view partly in section of an illustrative embodiment of the stack supporting and feeding mechanism of my invention; 60

Fig. 2 is a similar view showing part of the stack supporting and feeding mechanism in connection with a machine for operating 65 on the sheet material;

Fig. 3 is an end view of said stack supporting and lifting mechanism looking at Fig. 1 from the left;

Fig. 4 is a plan view of the operating 70 means for the stack lifting and sheet feeding mechanisms;

Fig. 5 is a detail view showing a yielding connection between a gear wheel on the main feeding shaft and said shaft; and

Fig. 6 is a sectional view showing a clutch 75 mechanism on said main feeding shaft.

In the illustrative machine the stack of sheets 8 rests upon a support 10 carried in a carriage 12 provided with two of these supports 10 as will be evident from an inspection of Fig. 3 of the drawings, the carriage being movable along tracks 14 to present one stack in operative position to have sheets fed therefrom while the operator is stacking sheets on the other support. After 80 sheets have been completely fed from one support 10 the carriage is moved laterally on the track to bring the other support with its stack of sheets in position below the sheet feeding means, stops 16 (Fig. 3) being positioned at the ends of the tracks 14 to determine the position of the carriage so that the selected stack is directly beneath the sheet feeding means to be hereinafter described. 85

The frame 18 of the machine in the construction shown comprises vertical posts 20 having slidably mounted thereon brackets 22 and 24 which provide flat surfaces engaging under the ends of the support 10, so that as the brackets are moved upwardly along 100 the posts, the support 10 with its stack of sheets is carried upwardly. The means for lifting the support 10 comprises in the illustrative construction a shaft 26 mounted in

the frame of the machine to extend longitudinally of the stack and of the support 10 and is provided at one end with a double drum 28 and at the other end with a single drum 30. It will be understood, however, that the same kind of drum, either single or double, may be provided at both ends of the shaft. The operating parts for the stack lifting mechanism are mounted at one end of the top plate of the frame 18 and hence it is possible to narrow the plate, reducing it in size at the other end simply for the purpose of saving material. For this reason the two vertical posts 20 at the smaller end of the top plate are located relatively close together and hence the bracket 22 sliding on these two posts is short and can be conveniently lifted by one cable 32 attached at its lower end at approximately the center of the bracket 22 and passing over an idle pulley 34 to the drum 30 to which it is attached and around which it is wound when the shaft 26 is rotated. At the other end of the machine frame, the posts 20 are spaced a considerable distance apart so that the bracket 24 which is slideable on these posts is much longer than the bracket 22 and hence two cables 36 and 38 preferably are used to lift bracket 24, one being attached at each end of the bracket 24 and passing over idler pulleys 40 and 42, respectively, to the double drum 28 to which the cables are attached and upon which they are wound simultaneously in the same direction, thus operating together to lift the bracket 24 evenly along the supporting posts 20. In this arrangement of cables it will be noted that the cable 38 passes over its idler pulley 42 and first around the upper surface of the drum 28 while the cable 36 passes over its idler pulley 40 and first on the under surface of the same drum. Thus both cables are wound in the same direction upon the turning of the drum and shaft 26.

The means for feeding the sheets from the top of the stack comprises, in the illustrative machine, feed wheels 44 having teeth 46 adapted to engage in the upper surface of the sheet being fed, the said wheels or rolls being driven from a shaft 48 which is operated in timed relation with the feed rolls 50 of a heel lift cutting machine 52 (Fig. 2) illustrated to show one application of my invention. In the machine 52 the feed rolls 50 are driven from the counter shaft 54 through a link connection 56 to an arm 58 having operative connections with the said feed rolls 50. Extending from the arm 58 is a link 60 pivoted to an arm 62 fixedly attached to one end of shaft 64, the arrangement being such that the shaft 64 is rocked with each rocking movement of the arm 58. Mounted yieldingly on the other end of the shaft 64 through a spring-pressed member 65 is a clutch device 66 of the well-known Horton type designed to clutch the gear

wheel 68 to the shaft upon rotation of the latter in one direction only, thereby transmitting intermittent movement to the gear wheel 68 in one direction, by which means intermittent feeding movement of the feed rolls 44 is produced through connections comprising a gear wheel 70 fixedly attached to shaft 48, said gear wheel 70 being indicated in dotted lines in Fig. 1 of the drawings, an intermediate gear 72 being interposed between the gears 68 and 70. The connections thus described between the feed rolls 44 and the feed rolls 50 are such that both feed rolls are intermittently driven in the same direction and at the same speed so that sheets of material fed from the top of the stack are properly engaged by the rolls 50 and fed into the heel lift cutting machine. The spring pressed member 65 which is splined on the shaft 64 permits of a turning movement of the shaft 64 in the feeding direction without turning gear wheel 68 should there develop excessive resistance to the rotation of the feed rolls due to obstruction or to any other cause. As each sheet is fed from the top of the stack the whole stack is lifted so as to present the new top sheet in proper position for feeding, that is, in a position in which it is pressed against the feed rolls 44. This stack lifting mechanism has already been described with the exception of the automatic control which determines the extent of the upward movement of the stack which must necessarily be limited to the thickness of the sheet of material which has just been fed from the top of the stack.

In the illustrative machine, the means for controlling the stack lifting mechanism comprises the presser foot 74 mounted in a casing 76 for vertical movement, means being provided, comprising a spring 78, for urging the presser foot yieldingly in the direction of the stack of sheet material and permitting the presser foot to move upwardly with the stack until the latter comes in contact with the feed rolls 44 and other rolls 80 which are idly mounted in brackets 82 extending downwardly from the top frame of the machine, the latter rolls assisting to maintain the stack in horizontal position. The means for driving shaft 26 comprises preferably a shaft 84 mounted in bearings 86 on the top of the frame 18 and arranged to be driven from the shaft 64 by connections comprising arms 88 and 90 fixedly attached, respectively, to the shafts 64 and 84, said arms being connected by a link 92 pivotally connected to the arms. Fixedly attached to the shaft 84 is an arm 94 carrying a pawl 96 adapted to engage with a ratchet wheel 98 loosely mounted on the shaft 84, a gear wheel 100 being fixedly attached to the ratchet wheel 98 and arranged constantly in mesh with a gear wheel 102 fixedly attached to a counter shaft 104.

The latter shaft has fixedly attached thereto a worm 106 (Fig. 4) which is arranged in mesh with a worm gear 108 normally clutched to the shaft 26 by detachable 5 clutching means comprising a member 110 which may be shifted manually on the shaft 26 to permit of rotation of the shaft independently of the gear wheel 108. If the pawl 96 were allowed to engage the ratchet 10 wheel 98 at all times and under all conditions, the shaft 26 would be caused to rotate during the same periods and at the same speed as the shafts 64 and 84. In order to control the rotation of the shaft 26 operative 15 connection between the pawl 96 and its ratchet wheel 98 is determined by means of a shield member 112 pivoted loosely on the shaft 84 and connected to the presser foot 74 by means so arranged as to interpose the shield between the pawl 96 and its ratchet wheel when the stack is positioned with the topmost sheet against the feed rolls 44. Upon removal of the top sheet so that the presser foot drops into contact with the 20 next subjacent sheet, the shield is moved to uncover the ratchet wheel 98 and permit the pawl 96 to engage therewith so that the shaft 26 may be driven through the connections already described to cause a lifting 25 of the stack. The connections between the shield 112 and the presser foot 74 are shown to comprise an arm 114 fixed to a stub shaft 116 provided with a segment rack 118 (Fig. 1) arranged constantly in mesh with rack 30 teeth 120 on the member 74. Pivottally connected to the upper end of the lever 114 is a link 117 having its other end pivotally connected to the shield 112.

In order that the shaft 26 may be operated manually to lift the stack support, the shaft 104 is provided with a hand wheel 121 (Fig. 4) and turning of this shaft through the direct connections comprising the worm 106 and the gear wheel 108 results in the 40 rotation of the shaft 26, there being at no time anything in the connections to prevent rotation of the shaft in a direction to lift the stack since the driving connections comprise, as pointed out, the ratchet wheel 98 and the pawl 96 which are so arranged that the ratchet wheel may turn in the direction to rotate the shaft 26 without interference by the pawl 96. Provision is also made for turning the shaft 26 in a direction to lower 45 the support for the stack, this construction comprising preferably a hand wheel 122 fixedly attached to the shaft and means for unclutching the gear 108 from the shaft 26, the said clutching and unclutching means 50 comprising, as stated, a clutch member 110 keyed to the shaft 26 for rotation therewith but slidable along the shaft so as to release the gear 108. Movement of the clutch member 110 away from the gear 108 is 55 carried out manually by connections to the

handle 124 comprising a forked member 126 engaging a collar 128 fixedly secured to the clutch member 110. As shown in Fig. 1, a bar 130 slidably mounted in the post 132 connects the bifurcated member 126 with the handle 124. When the stack of material on one of the supports has been entirely fed away from the support, the latter may be quickly lowered and the lifting mechanism returned to initial position simply by manipulation of the handle 124 which frees the shaft 26 so that the latter may be rapidly turned under control of the hand wheel 122 to permit the dropping of the stack support. When the empty support has been returned to the bottom of the carriage the latter is shifted to bring a fresh stack of material above the supporting brackets 22, 24 of the stack lifting mechanism and the operations are repeated by which the stack is lifted and the sheets periodically fed therefrom, as above described.

The carriage 12 comprises bottom bars 134 provided with bearings for the axles of the wheels 136 which support the carriage on tracks 14 and top bars 138 slidably in guideways 140 in the top plate of the frame 18. Connecting the bottom and top bars of the carriage are vertically arranged bars or posts 142, six in number and fixedly attached at their ends to the top and bottom bars respectively. Extending through and rigidly connecting the bars 142 in pairs from front to rear of the carriage are rods 144 carrying spacing and strengthening rolls 146. Carried by the rods 144 are vertically arranged plates 148 against which the front ends of the sheets are positioned in stacking the sheets on the support 10. These plates 148 serve not only to position the stacks but to retain the sheets in position during sheet feeding operations, the arrangement being such that the top sheet only can be fed forwardly through the operation of the feeding roll 44, the subjacent sheets being retained by the plates 148, as will be clear from an inspection of Figs. 1 and 3 of the drawings. As the top sheet leaves the stack of sheets the support 10 carrying the stack is raised a distance corresponding to the thickness of the sheet which has just been fed, thus bringing the new top sheet into contact with the feed roll 44 and in position to be fed over the upper edges of the plates 148. As before stated, when the sheets from one stack have been entirely fed from the support 10, the said support may be quickly lowered by unclutching the shaft 26 from its driving mechanism and permitting the shaft to turn under manual control exerted through the hand wheel 122 until the support 10 again rests on the bottom bar 134 of the carriage. The carriage is then shifted to bring the other support with its stack of sheets in proper position beneath the feed 130

roll 44 when the machine may again be operated to feed sheets from the fresh stack while the operator is loading sheets into the empty portion of the carriage. Since the 5 machine is entirely automatic in its sheet feeding operations one operator may readily take care of several machines by maintaining the supply of sheets on the carriage and shifting the carriage as required.

10 Having described my invention, what I claim as new and desire to secure by Letters Patent of the United States is:

1. In a machine of the class described, a vertically stationary feed roll for engaging 15 the upper surface of the topmost sheet to feed the same from a stack, means for lifting the stack toward the feed roll at the end of each sheet feeding operation comprising a shaft having a drum at each end 20 thereof and cables connected to the drums for supporting the stack, means for driving the feed roll and said shaft, and a vertically 25 slidable plunger closely adjacent to the feed roll and controlled by the stack for controlling the connection of said driving means with said shaft.

2. In a machine of the class described, means for feeding sheet material from a stack comprising a vertically stationary feed 30 roll, means for rotating the feed roll to feed the sheet material, means for lifting the stack of sheet material toward the feed roll, means comprising a pawl and ratchet mechanism for operating said lifting means, and 35 means controlled by the stack for rendering said pawl and ratchet mechanism operative when the top sheet has been fed from the stack in order to bring the stack into contact with the feed roll for a feeding operation of 40 the next top sheet.

3. In a machine of the class described, means for supporting two stacks of sheets comprising a carriage having movable supports for the stacks, means for lifting a 45 stack on either support selectively, a frame having vertically arranged posts carrying brackets slideable thereon, said carriage being movable to position one or the other of said supports selectively in position above 50 said brackets so that as said brackets are raised the support is carried upwardly therewith, and power means for lifting the brackets controlled by a member resting on the upper surface of the stack.

55 4. In a machine of the class described, means for feeding sheet material from a stack comprising a feed roll for engaging rotatably the topmost sheet of the stack to feed the same, means comprising a shaft for 60 lifting the stack into contact with the feed roll after the feeding of each sheet of material, means for intermittently driving said feed roll and said shaft, and means controlled by the stack for controlling the operation of said shaft.

5. In a machine of the class described, means for supporting a stack of sheets, means for lifting the support intermittently comprising a shaft, means for driving the shaft comprising a pawl and ratchet mechanism, a movable member for controlling the engagement of the pawl with the ratchet, vertically fixed members for engaging with the top of the stack to limit positively the upward movement of the top sheet, a presser 70 foot for engaging the topmost sheet of the stack close to one of said fixed members, and connections between the presser foot and said movable member to control the latter to permit the engagement of the pawl 75 with the ratchet after the feeding of each sheet from the top of the stack.

6. In a machine of the character described, a support for a stack of sheets, a vertically stationary feed roll for feeding 80 the sheets one at a time from the top of the stack, means spaced from the feed roll a distance corresponding to the thickness of one sheet for holding all except the topmost sheet from movement in the feeding direction, power means for lifting the stack, and 85 means controlled by the stack for controlling said power means so that the stack is elevated to present each successive topmost sheet in feeding position as soon as the preceding sheet has been fed by the feeding means.

7. In a machine of the character described, a support for a stack of sheets, means comprising a vertically stationary 100 feed roll for feeding the sheets from the top of the stack, means for elevating the stack subsequently to the removal of each successive topmost sheet, a retaining plate at the front of the stack spaced from the feed roll 105 a distance corresponding to the thickness of a single sheet and operative to retain all but the topmost sheet of the stack against movement in the feeding direction, and means arranged to be held yieldingly in contact 110 with the stack of sheets for controlling the stack lifting means.

8. In a machine of the character described, a support for a stack of sheets, a feed roll and another roll mounted so as to be stationary in a vertical plane and rotatable during the feeding of sheets successively from the top of the stack, means for elevating the stack in the intervals between sheet feeding operations, and a member arranged to engage the topmost sheet at a point between the rolls for controlling said stack lifting means.

9. In a machine of the class described, a support for stacks of sheets, a plurality of 125 rolls for engaging the top of the stack spaced from each other in the direction of the length of the stack, means for lifting the stack to present the top sheet in contact with said rolls, a retaining member at the 130

front of the stack spaced from the adjacent roll a vertical distance corresponding to thickness of a single sheet and operative to retain all but the topmost sheet of the stack 5 against movement in the feeding direction, means for feeding the successive topmost sheets from the top of the stack, and a mem- ber arranged to engage the topmost sheet at a point between certain of the rolls for controlling the stack lifting means. ¹⁰ In testimony whereof I have signed my name to this specification.

WILLIAM C. BAXTER.
